UNITED STATES PATENT OFFICE.

PAUL OTTO BOESKE, OF MANTON, RHODE ISLAND.

AIR-REGULATOR FOR ORGANS.

1,074,486.

Specification of Letters Patent. Patented Sept. 30, 1913.

Application filed July 10, 1912. Serial No. 708,614.

To all whom it may concern:

Be it known that I, PAUL O. BOESKE, a citizen of the United States, residing at Manton, in the State of Rhode Island, have 5 invented new and useful Improvements in Air-Regulators for Organs, of which the following is a specification.

This invention relates to air regulators for pipe organs and the like, the object in 10 view being to provide means for automatically throwing the air pump out of operation, when the bellows are filled, thereby doing away with the usual safety valve now employed on bellows, and the constant disagreeable noise which has been found annoying to choirs and persons located adjacent 15 to the mechanism of the organ.

With the above and other objects in view, the invention consists in the construction, 20 combination and arrangement of parts, as will be hereinafter more fully described, illustrated in the accompanying drawings, and pointed out in the claims hereunto appended.

25 In the drawings: Figure 1 is a side elevation of the mechanism for throwing the air pump into and out of operation. Fig. 2 is a plan view of the same. Fig. 3 is a detail view of the slotted arm.

30 Referring to the drawings, 1 designates the crank shaft of the air pump to be used in connection with organs for filling the bellows.

35 In carrying out this invention, fast and loose pulleys 2 and 3, respectively, are mounted on one end of the crank shaft 1, and are adapted to receive a driving belt 4 from a suitable motor. The belt passes through the eye 5 of a slideable belt shifting 40 member 6 mounted to slide in one or more bearings 7, as shown, so as to carry the belt either on the fast or loose pulley, and alternately from one pulley to the other.

45 8 designates a bell crank lever which is fulcrumed, at 9, on a suitable pin or stud supported in any convenient way, said lever comprising a short arm 10 which is terminally connected by a pivot joint to the adjacent end of the belt shifting member, as 50 shown. The longer arm 11 of said lever is actuated by an arm 12 secured to the movable side 13 of the bellows, so as to rise and fall therewith. Intermediate its ends, the said arm is provided with a semi-circular

offset 14 to dodge the crank shaft 1, and at 55 its outer extremity, said lever is provided with an upstanding extension 15, in which is formed a vertical longitudinal slot 16, in which the longer arm of the bell crank lever is received.

60 The length of the slot 16 is adjustable by means of a stop 17, extending across the slot and made adjustable up and down by providing the opposite portions of the extension with openings to receive the stop, which 65 may be in the form of a bolt, screw, or pin. The idea of rendering the stop 17 adjustable is to regulate the point at which the arm carried by the bellows will begin to act on the longer arm of the bell crank lever, for 70 the purpose of shifting the belt from the fast pulley onto the loose pulley.

75 It will now be seen from the foregoing description, taken in connection with the accompanying drawings, that as the bellows 80 fills, the arm carried thereby will move upward, and when the stop 17 comes into contact with the bell crank lever, the latter will be swung on its fulcrum, thereby operating the belt shifting element and throwing the 85 driving belt from the fast pulley onto the loose pulley, thereby terminating automatically the operation of the crank shaft of the pump. As soon as the air begins to exhaust from the bellows, the belt shifting element will, in the same manner and by the same means, return the belt from the loose pulley to the fast pulley, thereby again throwing the pump into operation. By the mechanism described, it is practicable to do 90 away with the usual safety valve now in common use on bellows at the same time dispensing with the disagreeable noise accompanying the use of such device.

95 What is claimed is:

1. The combination with a bellows, of fast and loose pulleys on the crank shaft of the air pump, a belt passing around said pulleys, an arm projecting from the movable side of the bellows and having a slotted extension formed with a longitudinal series of holes, a belt shifting member, a lever connected to said member and passing through the slotted extension of the arm of the bellows, and a stop insertible in any of said 105 holes.

2. The combination with a bellows, of fast and loose pulleys on the crank shaft of the

air pump, a belt passing around said pulleys, an arm projecting from the movable side of the bellows and provided with a slot, a belt shifting member, a lever connected to 5 said member and passing through said slot, and a stop extending across the said slot and made adjustable lengthwise of the same.

In testimony whereof I affix my signature in presence of two witnesses.

PAUL OTTO BOESKE.
